GEORGE HUNTRESS GRANT, OF RICHMOND, INDIANA.

Letters Patent No. 88,563, dated April 6, 1869.

IMPROVED SCHOOL-DESK AND SEAT.

The Schedule referred to in these Letters Patent and making part of the same.

To all whom it may concern:

Be it known that I, GEORGE HUNTRESS GRANT, of Richmond, in the county of Wayne, and State of Indiana, have invented certain new and useful Improvements in School-Desks; and I do hereby declare that the following is a full and exact description thereof, reference being had to the accompanying drawings, making a part of this specification.

The nature of my invention consists in so adjusting the leaf of a school-desk, that it may be slightly raised and withdrawn, and then let down, or folded with the desk, thereby closing the book-box; and in providing one or more sunken panels on the top of the desk, for the reception of the requisite ink-well, pens, and pencils, or for other purposes, as may be desired.

Also, my invention further consists in pivoting the seat to arms that are hinged, or pivoted to the standards, whereby the folding, or revolution of the seat may be accomplished from either edge of the same, and with equal facility.

To enable others skilled in the art to make and use my invention, I will proceed to describe the same with reference to the drawings, in which—

Figure 1 is a perspective view of my improved desk, and

Figure 2 is an end elevation of the same.

Figure 3 represents a plan view of the under side of the seat, and a section of the same is shown in Figure 4.

Figure 5 is an enlarged view of a portion of the end of the desk.

Similar letters in the different figures refer to like parts.

The leaf A is provided, at either end, with a batten, W, that engages with a projection, Z, on the cast-iron standards N N.

The connections, H H, consist of small curved bars of metal, one end being pivoted to the battens W W, and the other to the standards N N, in such a manner that the line of the pivots is inclined to the horizontal plane.

By means of the above-described mode of attaching the leaf A, it may be slightly raised and withdrawn, until the battens W W are released from the projections Z Z, when it will readily revolve into the position shown by dotted lines in figs. 2 and 5.

The pins n n are designed to stay the connections H H, when they have moved far enough to allow the leaf to revolve.

The book-box is provided with a cover, P, below the leaf, so that when the leaf is revolved, the books in the box are completely enclosed, and free from dust.

Sunken panels may be made in the top of the desk by removing portions of the board G, as shown at O, fig. 1.

The seat B is pivoted to the arms C C, as shown at h h, the arms being hinged, or pivoted to the standards at l l.

By raising the back part of the seat, the whole may be revolved into the position shown by red lines in fig. 2.

By this method of revolving the seat, the smooth upper surface of the same is kept outward, while the attachments on the under side are next the desk, where they are not liable to catch and injure the clothing, as is the case when the seat is folded in the usual manner.

Should it become desirable, the seat may be rigidly secured to the arms C C, by means of screws, inserted through holes, provided for that purpose, in the arms.

A slate-rack, D, is provided on the under side of the seat, with flexible straps V V, that are attached at one end to the seat B, and at the other to the board D, thus providing for the retention of slates, should they be introduced from either side, as will be desirable when the seat is revolved in the usual manner, or from the back part, as represented by red lines in fig. 2.

Having thus fully described my said invention, What I claim, and desire to secure by Letters Patent, is—

1. In combination with the leaf A, the hinged connections H H, battens W W, and stops Z Z, when constructed and arranged substantially as herein described.

2. Pivoting the seat B, near its front edge, to the hinged arms C C, for the purpose and in the manner specified.

GEO. H. GRANT.
